UNITED STATES PATENT OFFICE.

JOSEPH C. FOWLER, OF WASHINGTON, DISTRICT OF COLUMBIA, ASSIGNOR
OF ONE-HALF TO LEMON G. HINE, OF SAME PLACE.

MACHINE FOR PRODUCING TYPE-BARS.

SPECIFICATION forming part of Letters Patent No. 510,853, dated December 12, 1893.

Application filed April 6, 1893. Serial No. 469,335. (No model.)

To all whom it may concern:

Be it known that I, JOSEPH C. FOWLER, a citizen of the United States, residing at Washington, in the District of Columbia, have invented new and useful Improvements in Machines for Producing Type-Bars, of which the following is a specification.

My invention relates to that class, or type of mechanism employed for handling the matrices from which, when placed in orderly arrangement, a line or some portion of a line of type is cast. These are commonly known by the name of "linotype" machines.

It is one essential purpose of my said invention to simplify and improve the construction and operation of the mechanism shown and described in the Letters Patent granted and issued to me upon the 30th day of August, 1892, No. 481,920, for a machine for casting type-bars.

It is one specific object of my present invention to provide a machine of this class in which the magazine holding the matrices and spacers shall be of circular, or substantially circular form, the cells being arranged upon the exterior of a shell rigidly mounted upon a fixed vertical axis, and to combine therewith novel and simple means for releasing the matrices from the cells and for preserving the orderly succession established by the order of their release.

It is a further purpose of my invention to provide novel means for enabling the matrices to pass by their own gravity, as they are released from the magazine cells, to and into an assembling space, or line-chamber, thereby dispensing with the mechanism heretofore employed for these purposes; to provide a novel and simple escapement-mechanism for insuring the release of the matrices separately and for preventing the escape of more than one from the same cell and in response to the same impulse of the key by which the selection is made; to combine with a matrix magazine and with a suitable release, or escapement-mechanism, a novel and simple assembling-apparatus, and means for ejecting the matrices after the type-bar is cast, at the same point in the same end of the line-chamber at which they enter.

It is my purpose, also, to provide a ma-

chine of this kind with an entirely novel apparatus for lifting the matrices from the line-chamber to the receiving-end of the magazine, and to combine with the lift novel and simple distributing devices to carry the matrices over and automatically drop them into the cells of the magazine, each into its proper, individual compartment.

It is my purpose, too, in organizing this machine, to combine with a suitable support, having a plurality of line-chambers simple means for manipulating the matrices and assembling them in one of said chambers, means for rectifying, compressing, and holding the line, during the operation of casting, and an intermittently rotating mold-carrier having a plurality of molds of such novel construction and function, that the respective movements of the support containing the line-chambers, as well, as the movements of the mold-carrier may be made without interference, the mold accurately aligned and closed upon the line of matrices, and the cast made; to combine with said mold a vibratory melting-pot of novel construction means for vibrating the same to form a close joint between its exit-opening and the mold, and mechanism for forcing the melted metal therein at the proper moment, means for insuring the automatic and accurate engagement of the mouth of the pot with the open end of the mold, and the automatic separation of said parts after the cast is made and before the line of matrices is advanced to its next successive position where the matrices are distributed.

It is also the purpose of my invention to provide novel means for dressing the base or lower edge and the sides of the type bar.

It is another purpose of said invention to assemble the matrices in orderly arrangement in the several line-chambers successively, to introduce them at a single point, to advance them in the line-chamber as they enter, to carry the assembled line to a different position or point, for casting the type-bar, and to effect this movement without meeting with, or causing, obstruction by the presence of the matrix-advancing devices or the parts by which the line is compressed and held for the purpose of casting; to remove the matrices for distribution at a third point, or position

of the assembled line, and to eject them automatically from the line-chamber at the same single point at which they were introduced, and to remedy, or remove, the difficulties frequently experienced heretofore in making a rapid and accurate distribution of the matrices, after the type-bar is cast, thereby enabling me to use a matrix-magazine of comparatively small proportions, to reduce the number of matrices to the minimum and, by their speed and accurate return to the proper cells of the magazine, always maintain therein a supply fully equal to the maximum possible demand, the three distinct operations of assembling, casting, and distributing being carried on simultaneously, at the three separate points referred to.

Finally, it is my object to simplify and improve the construction and function of the individual elements of the machine, to combine the same effectively and with the utmost simplicity, to render the operation more accurate and expeditious and wholly automatic, whereby the mechanism shall require but a single operator whose attention may be concentrated upon the key-board by which the matrix-selection is effected, the productive capacity of the machine being thus rendered from two to three-fold, as compared with one requiring two operatives, or with one in which the full sequence of successive operations must be completed for the production of each finished type-bar.

To the several purposes thus briefly stated, the invention consists in the novel features of construction and in the new combination of parts particularly pointed out and defined in the claims appended to this specification, in which the invention will be so fully explained as to enable those skilled in the art to which it pertains to make, construct and use the same.

For the purpose of this description, reference will be made to the drawings accompanying this application, in which—

Figure 1 is a front elevation of a machine embodying my invention, the upper portion of the matrix-magazine and lift or elevator, being broken away. Fig. 2 is a plan view of the machine. Fig. 3 is a view taken from the rear side of the machine, showing the magazine, the lift, or elevator, and the escapement-mechanism, one half the magazine being in vertical, axial section. Fig. 4 is an elevation taken from the end of the machine, showing the mold-carrier partly broken away to disclose the matrix-line, the line-compressor, and portions of the type-bar ejector, the milling and the matrix-ejecting devices and the lift, the lower end of the jacket enveloping the latter being broken away. Fig. 5 is a detail plan view showing the plurality line-chambers and the support, preferably termed the "square," by which they are contained; said figure also including the lift, in horizontal section, and parts of the line-driving devices, the line-compressor and holder, and

the mold. Fig. 6 is a detail perspective view, showing the pusher and the latch of the assembling-escapement. Fig. 7 is a detail section of the spring-housing and the pusher. Fig. 8 is a detail plan view of the distributor wheel. Fig. 9 is a plan view of the receiving-end of the matrix-magazine, the inclosing top and distribution-bar removed and the lift being shown in horizontal section. Fig. 10 is a detail view showing the upper surface of the rotary matrix-table, usually termed the "sequence" disk, together with the assembling-chute, the relative position of the "square" being indicated in this and in the preceding figure by dotted lines. Fig. 11 is a detail view showing, in vertical section, one of the cells of the matrix-magazine, the distribution-bar and distributor-wheel and the upper portion of the lift, the jacket of which is partly broken away to expose the lifting spiral. Fig. 12 is a detail section, taken in the horizontal plane 12—12, in Fig. 11. Fig. 13 is a diagram showing the key-board and key-levers, to illustrate the manner of extending the lever-connection from the key-board entirely around the exit-end of the magazine with the least possible bending of said levers. Fig. 14 is a sectional elevation of the sequence-disk the assembling-chute, and the cell-chutes at the lower end of the magazine, part of the outer drum of the chute-ring being broken away. Fig. 15 is a detail perspective of the sequence-table and assembling-chute, the chute-ring being removed. Fig. 16 is a side or edge elevation of the square, partly in section, together, with a portion of the line-advancing device or pusher, and the assembling-escapement. Fig. 17 is a detail view, showing the interior face of one of the walls of the magazine, together with a part of the distribution-bar. Fig. 18 is a sectional view, the section plane being taken horizontally immediately beneath the "square," in Fig. 1. Fig. 19 is a detail section showing part of the "square," and the matrix-ejector and its operating devices. Fig. 20 is a sectional view showing part of the shaft operating the ejector, and the clutch-connection. Fig. 21 is an end view of the clutch-disk on the sleeve carrying the bevel gear through which revolution is communicated to the ejector. Fig. 22 is an end view of the other member of the ejector clutch-connection shown in Fig. 20. Fig. 23 is a face elevation of the mold-carrier, showing the plurality of molds and the rectifying-rules. Fig. 23^a is a detail perspective of the separator-ring and cam. Fig. 24 is a central, vertical section of the mold-carrier and its immediate adjuncts, together with that portion of the "square" containing the matrix-line, and the matrix rectifying device and the gearing operating it. Fig. 25 is an end-view of the bevel gear shown in Fig. 24, showing the matrix rectifying devices; the position of the square being shown by dotted lines. Fig. 26 is a detail view of the face of

the bearing shown in Fig. 24, for supporting the shaft of the mold-carrier. Fig. 27 is a detail view showing the automatic device for stacking the finished type-bars, as they are driven out of the molds. Fig. 28 is a detail view showing the milling-devices which dress the parallel flat faces of the type-bars as they are driven out of the molds, and showing, also, the stacking device and part of the arm which operates it. Fig. 29 is a detail perspective of the planing tool. Fig. 30 is a central vertical section of the melting-pot, or crucible, showing, also, the means for vibrating the pot and for operating the piston, or plunger. Fig. 31 is a view of the parts shown in Fig. 30, in elevation, the point of view being upon the side adjacent to the mold. Fig. 32 is a detail perspective of one of the bracket-supports for the vibrating melting-pot. Fig. 33 is a detail side elevation of a key, key-lever and vertical bar for actuating an escapement; and Fig. 34 is a detail sectional view of a part of the assembling table or square.

The figures briefly described above are all drawn to a scale indicated upon each sheet, at the top, by the words " $\frac{1}{4}$ size," " $\frac{1}{2}$ size,"—" $\frac{1}{2}$ size"—"full size," several of the detail views representing certain parts of the actual size used.

In the following description of parts I will follow, as nearly as circumstances permit, the order of mechanical operation, this being the natural order of explanation, besides having the advantage of permitting a description of function to accompany those explanations of construction and arrangement upon which individual and co-ordinated functions depend. After pointing out, therefore, the essential parts of the machine-frame, I will commence with the operation of assembling the matrices in line, for which purpose they must be released from the cells of the magazine in response to impulses transmitted from a key-board to an escapement-mechanism. Re-

leased from the cells, they must pass to and enter a line-chamber by their own gravity, and they must be intermittently advanced therein in the order of their release from the cells. The completed line is carried by the "square" to a farther point, where it is compressed and rectified, and during its movement an independent mold-carrier also moves to bring one of a plurality of molds into position for co-acting with the line of matrices, the intaglios of which form practically, the bottom of the mold. The latter being automatically aligned and closed, the melting-pot is moved up and its exit-openings brought into communication with the open end of the mold, during which movement the matrix-line is compressed and rectified; the plunger is then operated and melted metal is thrown into the mold-space and against the intaglios of the matrices to cast the type-bar. The pot then moves back, the mold separates from the "square," and the latter receives an intermittent movement thereby bringing the line of

matrices from which the cast has been made to a still farther point or position, where the matrices are driven out for distribution to the cells of the magazine. During this second movement of the "square," the mold-carrier also makes an intermittent advance to bring a second, empty mold into position to co-operate with a second line of matrices in a second line-chamber of the "square." The type-bar, which is cast just prior to this movement, remains in the mold in which it is formed until the said movement is completed, and during said advance of the mold-carrier the base, or lower edge of said type-bar, is planed off and brought into true relation to the type-face, in order that the type may be exactly "type-high" in every bar. Having accomplished this movement, the mold-carrier stops, the type-bar is driven out, and as it emerges its flat, parallel faces are milled or dressed and as it wholly emerges from between the milling devices it is stacked upon a suitable table in its proper order, relatively to those preceding. During the ejection of the type-bar and the milling of its opposite faces, the line of matrices from which it was cast are driven out of the line-chamber, and carried up by the lift to the distribution-mechanism, whence they are returned to the cells of the magazine from which they were taken. Simultaneously with this operation a second type-bar is in process of casting at position number two, and the operator at position number one is also filling a third line-chamber in the "square" with a new line of matrices. The manipulation of the key-board, by which the matrices are selected and released from the magazine, and the operation of a pedal by which the intermittent movement of the square and mold-carrier is initiated, are the sole functions devolving upon the operator.

The type-matrices, indicated by the reference-numeral 1 Fig. 3, are substantially of the usual, well-known form, each having an intaglio of some letter or character suitable for use in printing, formed in its edge at the point 2. These matrices are provided, at one end, with a notch, of substantially or approximately the form of the letter V, and upon the interior edges thereof are the hooks, or points 3, having a different arrangement in each matrix, and forming different combinations whereby their proper distribution is accomplished in the well-known manner. These matrices, in suitable number, are stored in a magazine and released therefrom in any desired alphabetical order, and I will now describe said magazine and explain the mechanism by which a single matrix can be obtained from any single cell in the magazine, at any moment. The magazine consists of a double, or inner and outer concentric metallic shell 3^a and 4 Figs. 3, 9, so arranged that a uniform space shall be preserved between them at all points. In external form it presents the appearance of an inverted, truncated cone having a small angle of obliquity,

as compared with its altitude. The inner shell 3 is supported at its lower or truncated end, by a thick collar 5, rigidly mounted upon a fixed vertical axis 6, which rises from a part 5 of the machine-frame presently to be described. At its upper end said inner shell is supported by an open frame, or skeleton disk 7, rigid upon the axis 6 and engaging the inner face of the shell a little below its end. 10 The lower collar 5 rests upon a vertical flange 8, forming part of a circular base 9 which is rigid upon the fixed axis 6. An outer flange 10, concentric with the flange 8, lies beneath and supports the lower end of the outer 15 shell 4. The flange 10 is preferably formed of a separate piece, though it may be a cylindrical continuation of the outer shell 4. The annular chamber between the adjacent faces of the two flanges 8, 10, is a very little 20 greater in width than the matrices, and between the flanges are mounted plates 12, extending radially, or nearly so, and having a downward inclination with a gentle curvature, as their lower ends are approached, 25 whereby they deviate to an angle between the vertical and horizontal, as shown in Figs. 3 and 14. This curvature is similar throughout the series of plates 12, which are arranged at intervals corresponding to the intervals 30 between the exit-ends of the cells in the magazine. With relation to these cells, the plates 12 form what I term cell-chutes, by which name I will hereinafter designate them, their function being explained at another 35 point. The annular space in which they are placed will be termed the chute-ring, in the following description. The cells of the magazine lie in the space inclosed between the adjacent faces of the inner and outer shells 3 and 4, the uniformity of such space being 40 maintained by partitions 13, (Fig. 9) inserted at any suitable intervals between the two shells. The magazine as a whole is rigidly held and rendered stable, by means of a 45 strong, tubular column 14, Fig. 3, bolted to the same rigid part of the frame which sustains the vertical axis 6, the upper end of the column being curved toward the middle portion of the exterior shell 4, to which it is 50 firmly united. At suitable intervals in the space between said shells are formed the cells, for the matrices, which each consists of two opposite slots, or channels, 15, so arranged that both lie substantially in a plane radiating 55 from the fixed axis 6. These slots or channels 15, extend from a point very near the top of the two shells 3 and 4, to the extreme lower end thereof, their dimensions being such as to receive and retain the laterally 60 projecting lugs at the ends of the matrices, but permit perfectly free movement in vertical planes. I prefer, in the present instance, to form these channels by planing away the metal upon the adjacent faces of 65 the shells 3 and 4, thereby leaving thicker portions 16 (Figs. 9 and 17) which fill the intervals between the cells. These portions are terminated, at a point a little below the upper end of the magazine, by a continuous, circular channel 17, cut to the same depth as the channels 15. The upper ends of the intermediate portions 16 are beveled off upon both sides about equally, thereby giving a downward convergence to the end-edges, upon each side of each channel. The space, or channel 17, between the pointed or angular ends of the parts 16, and a series of symmetrical and similar projections 18, is of such width as to permit the passage by a horizontal circular movement, of the laterally projecting lugs upon the lower ends of the matrices. Said channel is bounded, along its upper margin, by the horizontal lower edges of the symmetrical projections 18, the short vertical sides of which are in line with the corresponding sides of the portion 16, between the cells. The said projections 18 are thus separated by short slots, or channels 19, which coincide with the cells 15. The upper ends of said projections 18 are beveled off on both sides at the same angle with the bevels of the ends 16. The altitude of said projections, from the horizontal bases to the apices formed by their beveled upper ends, is such as to permit the upper and lower lugs upon the same side of a matrix to completely straddle the projection and move in a horizontal plane, one of said lugs traversing the space or channel 17, and the other passing just above the beveled ends of the projections 18. The special purpose of these features of construction will be pointed out in describing the distribution of the matrices, in which said parts perform important functions. The several cells 15, are thus arranged in a space which is circular, or annular in cross-section, and has a gradual contraction from the upper to the lower end, at which point they open above and immediately in front of the concave faces of the cell-chutes 12. As the matrices are dropped into the respective cells of the magazine, they pass down therein by gravity, until the matrix first introduced is arrested, a little above the exit-end of the cell, by an escapement-mechanism, the remaining matrices in the same cell being sustained by the lower matrix and by each other, the foot of each resting upon the top of the one next below. The escapement-mechanism consists of a latch-bolt 20, Fig. 3, sliding in a substantially radial housing 21, its line of movement being at or about a right-angle to the line of movement of the matrices. This latch-bolt is thrown inward normally, by a spring 22, supported by the housing 21, its end pressing upon the outer end of the latch-bolt, and driving the same inward so that its point passes through a suitable opening in outer drum 4 and enters the outer channel 15, forming part of the cell in which the matrices stand. Standing in this position the bolt is controlled by a stop-shoulder 20^a and the first matrix descending encounters the point of said bolt, and is arrested, the outer lug upon its lower end pressing upon the point of the latch-

bolt. Within a chamber, or recess 23, in the housing 21, is arranged a lever 24, fulcrumed between its ends upon a pivot-pin 25, and having its rigid lower end or terminal 26 projecting inwardly and lying just within an opening in the top of the outer flange 10 inclosing the cell-chutes 12, but not projecting into the outer channel 15 of the cell. The upper end of said lever has any suitable connection with the latch-bolt 20, as, for example, that shown in Fig. 3, the end of the lever being rounded and laid in a seat or recess, in the lower edge of the latch-bolt, which lies directly over the chamber 23. As the latch-bolt and lever are flat and the former supported on all sides in the housing, this form of connection is preferable because of its simplicity and efficiency.

To operate the latch-bolt 20 the lower end of the lever must be thrown inward and as this movement withdraws the point of said latch-bolt from beneath the lug on the lower matrix-plate 1, the latter instantly drops by gravity, its movement being somewhat accented by the weight of the series of matrices stored in the cell. The same movement of the lever 24 which retracts the latch-bolt also throws the terminal 26 upon its lower end into the path of the same lug on the lower matrix which has been released by the point of the latch-bolt 20. This matrix, therefore, drops as far, only, as the exit-end of the cell in which it stands. By this descent its upper end passes the point of entrance of the latch-bolt, and as the entire line of matrices descends with it, the second matrix, which rests upon the first, is brought into such position, when the lower one is arrested by the terminal 26 of the lever, that the outer lug upon its upper end stands a little above the point where the latch-bolt 20 will enter the channel 15, upon the release of the lever 24. As the latter is under the control of the spring 22, so far as its inward movement is regarded, its restoration to normal position will take place instantaneously, upon the removal of the impulse given to the lever. This movement withdraws the terminal 26 and sets the lower matrix free, but as the point of the latch-bolt 20 is at the same instant, thrown into the channel 15, it is brought into the path of the outer lug upon the upper end of the second matrix thereby preventing its escape and holding the entire series of matrices which rest upon it. As long as the operator presses on a key the rigid terminal 26 of the lever 24 lies in the path of the matrices, but the instant the key is released the column of matrices acts directly on the pivoted lever 24 and swings it; so that the rigid terminal 26 is moved outward, and the lower matrix can pass down. At the same time the latch-bolt 20 is moved inward to hold the column of matrices. This result is insured by reason of the rigid terminal 26 lying to one side of a vertical line, taken through the pivot 25, when a key is depressed, whereby

the weight of the column of matrices on said rigid terminal 26 causes the lever 24 to swing on its pivot, so that the lowermost matrix can descend. By this means I do not necessarily depend entirely on a spring 22 for moving the latch-bolt into the path of the matrices when a key is released. 70

The housings 21 are arranged around about the base of the magazine, and lie in the same radial planes with the cells or substantially so. The outer edges of said housings extend somewhat below the base of the magazine, where they unite with a narrow, horizontal flange 27, which forms part of a circular jacket 28, closely surrounding the outer flange 10 of the chute-ring inclosing the cell-chutes. At its lower edge a second circumferential flange 29 is extended outwardly, at a point 85 not far from the bottom of the chamber inclosing the cell-chutes 12.

In the two horizontal flanges 27 and 29 are formed openings in which are placed a series of bars 30 Figs. 3 and 33, having substantially 90 vertical arrangement, their upper ends entering the chambers 23 of the housings 21 and having their extremities beveled upon their inner edges to form wedges, the entering ends of which point upward. These wedge-shaped ends lie in the narrow spaces between the outer end-walls of the housings and the lower ends of the levers 24, their outer, vertical edges supported by said walls and by the openings in the flanges 27 and 29, and their beveled or angular edges resting against or in close proximity to the outer edges of the levers 24 at the points where their lower ends curve, or bend inward, to form the terminals 26. To each bar is attached a spring 30^a, of 105 moderate tension, to restore the bars to their normal position after each stroke. The lower ends of said bars 30 are extended below the flange 29 and are connected to the keys of the key-board in the following manner. 110

It is evident that it is desirable, if not necessary, that the several keys which are pressed by the operator in order to release the matrices, should have, as nearly as possible, a uniform range of movement and should present substantially the same resistance to the finger when pressed, since marked differences in these respects would be extremely apt to cause inaccuracies, or to seriously impede the rapidity of the work by requiring specific attention to the extent of stroke of each key and in some of the number, perhaps, necessitating more than one impulse, or manual effort, to insure the complete operative movement of the keys. It is essential, therefore, 115 to avoid bending the key-levers at considerable angles, to make the connections as simple and direct as possible, and to so arrange the fulcrum points that each lever shall have the same acting distance, or relatively the 120 same. I arrange the key-board 31, Fig. 1, therefore, upon the front side of the machine, and mount the keys 32 in a casing 33, Fig. 2, in which their stems are vertical, the keys being 125 130

arranged in several banks, preferably varying in height, and operated like the keys of an ordinary type-writing machine. I have shown, in the present instance, thirty-two of 5 these keys, only, but this number may be increased as far as necessary, to correspond with the capacity of the magazine.

To the lower ends of the key-stems in the lowest bank of keys I connect the ends of a 10 series of key-levers 34 Figs. 3, 13, 33, which pass under, and at some distance below, the base of the magazine, the two longest levers being very slightly bent to pass on opposite sides of the fixed axis 6. The other ends of 15 these levers are pivotally connected, in any suitable manner, to the hanging ends of the bars 30 lying upon the other side of the axis 6, at points about midway of the connections to said bars and to the key-stems, said key-levers are fulcrumed upon forked posts 35 which rise from a supporting bar 36 arranged above the bottom of the casing 33. In like manner a second bank of keys, next to and at a higher level than the first bank, is connected to key-levers 34 which pass beneath the magazine and connect to the hanging ends of the bars 30 which lie upon opposite sides of the fixed axis 6, four of such key-levers being placed upon each side. As the key-levers last 20 named are arranged at a higher level, the bars 30 to which they are connected will be supported a little above the point of such connection, by a raised flange 29^a (Fig. 3). The sixteen key-levers thus described operate the bars 30 included in—or nearly in, the semi-circumference of the base of the magazine lying upon that side of the axis 6 farthest from the key-board. The second series of 25 eight key-levers is, like the second bank of keys 32, arranged at a somewhat higher level than the first series, and is fulcrumed upon supports 35, mounted upon a second and higher bar 36. The key-stems of the third bank are connected in substantially like manner and the fourth bank, which is highest and lies nearest the fixed axis 6 are connected to the bars 30 depending from the base of the magazine nearest to the key-board, their fulcrums having a like construction and support. This arrangement is simple and inexpensive and gives the necessary results without requiring a material extension of the casing 33. By pushing any key downward, the 30 bar 30 is driven up and its beveled edge is forced against the back of the lever 24, forcing its terminal 26 inward and withdrawing the latch-bolt 20. When the finger is removed from the key the bar 30 is snapped downward by the spring 30^a, which also restores 35 the key and key-lever to normal position, while the lever 24 is returned to place by its independent spring 22.

Having obtained the matrices for the magazine and insured the exit of a single matrix, 40 only, in response to each single impulse from the key-board, it is now necessary to provide means for preserving their orderly sequence

and for their entrance to the space, or chamber, in which they are to be assembled which they will enter at a single point and in the 45 same order in which they are released from the magazine-cells. As these cells are arranged at intervals around a fixed point or axis, the matrices will be dropped at various points in the circular plane of the cells and 50 they must pass from such points to the single point where they enter the line of matrices in process of formation. Moreover, one or more matrices may drop very near this point of entrance to the line, and one or more at a 55 greater distance and it is evident that the latter may, and frequently will, be entitled to a position in the line of matrices preceding the former, but if the order of entrance to the line be, in any degree, proportioned 60 to the relative distances to be traversed in order to enter the line, there will be constant danger that the alphabetical arrangement will be destroyed. To meet both these contingencies I provide the following means. 65 Upon the fixed axis 6, Fig. 3, beneath the collar 9 is mounted a sleeve 37, its lower end resting upon a collar 38 rigid upon the said axis. Upon the upper end of said sleeve is a disk 39, the upper surface of which is intermediately beneath the open bottom of the chute-ring inclosing the cell-chutes 12, the periphery of said disk lying at a point a little within the inner face of the flange 10, which forms the outer wall of the chute-ring. Upon 70 the upper face of the said disk, adjacent to the fixed axis 6, is a slightly raised circular portion 40, Fig. 15, which extends to, or nearly to, the open bottom of the chute-ring. From the edge of this raised portion to the periphery of the disk the surface is slightly lowered 75 to leave an annular space 41, which is crossed at suitable intervals by ribs 42 of low relief. Upon the sleeve 37 is a pulley 43, by means of which the disk is driven at speed, its rotary movement being in the direction of curvature of the cell-chutes 12. At the left hand side of the fixed axis 6, and a little in front of the same, is arranged a spout-shaped line-chute 44, Fig. 14, one of its walls being curved 80 from the vertical chute toward the front of the machine and brought under the edge of the disk, bent upward in close proximity to said edge and then extended outward with its upper surface flush with the annular space 85 41 of the disk. This extended portion has a marginal flange, or rib 45, which extends backward and forms part of a hood 46 overhanging part of the downwardly curved wall of the chute. This hood rises above the surface of 90 the disk and from the inner side of the same extends an arm 47, substantially parallel with the ribbed edge 45. This arm crosses the annular space 41 of the disk in a line substantially tangent to the edge of the raised portion 40, 95 its end being curved slightly inward to cross the said edge and its lower edge lying as close as possible to the same, without actual contact with the ribs 42. The interior width be-

tween the arm 47 and the rib 45 is a little in excess of the maximum width of the matrices, measured from the extremities of their lateral lugs. The width of the annular space 40, as will appear from Figs. 10 and 15, is somewhat less, for a reason that will presently be shown. At its lower end the middle portion of the line-chute 44 is cut away, see Fig. 15, leaving two parallel sides 48 which retain parts of the inclosed space and form vertical guides in which the lugs on the matrices may move freely. The lower end of these guides 48 overhang one end of the line-chamber, so that the matrices may pass from the line-chute directly into the entrance opening of said chamber without changing the direction of movement given by the chute. The sequence-disk 39 is driven at uniform speed the number of revolutions in any given unit of time being somewhat in excess of the maximum number of matrix-selections possible within the same period. If, therefore, a matrix is released at any point within the circular series of cells, or at any distance from the entrance at the line-chute 44, it must inevitably reach the mouth of said chute before a second matrix can be dropped, and the proper alphabetical order will thus be preserved, and every matrix will be brought in the order of its release to the single point of entrance to the line-chamber. As the matrix passes out of the exit-end of the cell in which it is stored, it drops upon one of the cell-chutes 12, and slides down its concave face, the intaglio in its edge being outermost. From the cell-chute it slips easily and naturally upon the annular, depressed surface 41 of the sequence-disk, upon which it lies flat, the lugs upon its outer edge projecting over the periphery of the disk. As it passes between the rib 45 and the clearing arm 47, it is diverted from the line of circular movement, and partly by its own momentum and partly by the impulse given by that one of the ribs 42 which lies behind it, it is carried under the hood 46 and down the line-chute 44. During the instant it remains upon the disk it is held against outward displacement from centrifugal force by the surrounding outer wall 10 of the chute-ring, which descends as low as the plane in which the annular face 41 revolves. The line-chute descends to a point some distance below the sequence-disk, the extremities of its guides 48 hanging just above the part containing the line-chambers, said part as already mentioned being termed the "square." This square is shown in full size in Fig. 5. It consists of a quadrilateral 50 which is truncated at the four corners to remove the angles. Upon each of the four equal sides is formed a channel 51 Figs. 4 and 34 cut through the square from top to bottom and lying near to, and parallel with the outer edge. This channel is of a width capable of receiving the body-portion of the matrices which stand vertically and transversely therein. Parallel with said channel upon each side

thereof are narrow marginal spaces 52 upon the surface of the square and upon both sides of the channel 51. These spaces are of sufficient width to readily admit the upper ends of the matrices with the lateral lugs which cross said spaces 52, and rest thereon. Upon the inner side of the channel 51 the spaces 52 upon all four sides of the square are bounded by the vertical faces of a raised rectangular portion 53. Along the front of the square, upon each side, a plate 54 raises, forming a boundary to the outer space 52, its upper edge being of the same height as the raised portion 53, and flush, or nearly so, with the tops of the matrices standing in line. Looking at one of the edges of the square, a part of which is shown in Fig. 19, with the end portion broken away to show the interior of the line-chamber, it will be noticed that the inner vertical face 55 of the chamber 51 terminates a little above the under face of the square, see also Fig. 34, upon which is a plate 56, cut away to leave an open space conforming in width to the channel 51, its marginal portion in rear extending back to a narrow vertical face 57 lying in the same plane with the corresponding vertical face of the raised portion 53. A similar channel is formed upon the opposite side between the front vertical face of the channel 51 and the lower margin of the plate 56, upon that side. This channel is closed, upon the front side, by the vertical plate 54 which extends entirely over the edge, or vertical outer face of the square. These two channels admit the lugs projecting from the edges of the matrices at their lower ends, as clearly seen in Figs. 24, 34. In the vertical plate 54 is formed an opening 58, exposing the line of intaglios in the outer edges of the matrices in the line. This opening is of such length and width as to admit the mold (Fig. 24) when the latter is moved up to the position for casting.

The square 50 contains, as shown in Fig. 5, four separate line-chambers 51, arranged upon its four equal sides, each chamber being of the length of a line of matrices required in casting a type-bar of full column-width, measured alphabetically. The square is mounted upon a central sleeve-support 59, loose upon a vertical shaft 60 arranged upon the left hand of the fixed axis 6 of the magazine, and at the left of the operator as he uses the key-board, as in my Letters Patent before mentioned. An intermittent movement is given to the sleeve-support 59, by mechanism described hereinafter, by which it is turned in a horizontal plane through one-fourth of a complete revolution. The position of a square is shown in Fig. 1 and in dotted lines in Figs. 9 and 10, and its direction of movement is shown by the arrow in Fig. 5. At each of its movements, one of the line-chambers 51 is brought into such position that one of its ends is directly beneath the lower ends of the two guides 48 which terminate the line-chute 44, as seen in Figs. 5, 10 and 16. At this extremity of the chamber 51 is the ma-

trix-entrance formed by cutting away the edges of the margins 52 to form vertical slots 61, Figs. 5, 19, of a form and size permitting the ready passage of the lugs of the matrices. Each matrix, as it descends the line-chute 44 and reaches the terminal guides 48 is caught by an escapement device consisting of a latch-bolt 62, Fig. 16, sliding in the upper part of the housing 63, mounted upon 5 the inner side of the guides 48. With the latch-bolt 62 the end of the lever 64 has pivotal engagement said lever being fulcrumed upon a pivot 65 and its lower end being turned, or bent inward toward the line-chute. 10 The latch-bolt 62 is thrown in, so that its point lies in the path of the lateral lug on the inner side of the matrix by means of a spring 66, the entire escapement being substantially identical with that shown in Fig. 15 20 in connection with the cells of the magazine. As it is used at this point for one special purpose I will term it the line-escapement, its function being to prevent the lower one of the series of matrices standing end 25 on-end in the line-chute, from passing out of the latter until the preceding matrix has entered the line-chamber and been advanced therein far enough to remove it from the vertical line of movement of its successor. 30 I will now explain the means for advancing the matrices as they enter the chamber 51, and for operating the line escapement. Upon the front of the main frame A of the machine, (Fig. 1,) is mounted in suitable 35 bracket-bearings 67, bolted to said frame, a bar 68, in which is interposed a race-loop 69 which receives a wrist-pin 70, Fig. 6, carried by a disk 71, the latter receiving continuous revolution from a shaft 72, Fig. 18, having its 40 bearings in the frame A, the gear-connections therefore being explained at a farther point in the specification. The bar 68 Fig. 6, is arranged horizontally and substantially in the line of intersection of a vertical and a 45 horizontal plane, the former passing through the longitudinal center of the line-chamber, and the latter through the series of intaglios, as the matrices stand in the line. Upon the end of said bar next the square is mounted 50 a head 73 having upon its ends upper and lower parallel plates 74, which form a support for a rectangular housing 75. To the front face of this housing is attached the end of an elastic plate 76 which extends to the right 55 until its broadened end overlaps the race-loop 69, to which said end is rigidly fastened by screws tapped into a boss 77 or one of the vertical bars of said loop. The plate 76 is usually made of thin steel, but any other material having suitable elasticity may be used. The end of the housing 75 which is overlapped by said plate is loosely held by attachment in the space between the parallel plates, 74. The end of the housing nearest to the 60 square is open to receive the end of a pusher 78, capable of moving freely in the line of its axis but held by a spring at its farther limit 65

of projection from the housing 75. The square end of this lies in the housing 75 and is provided with a pin 79 which lies in a slot 80 in the wall of the housing. A spring 81 is located in said housing by which the pusher is normally projected, as in Fig. 7. The parts are so proportioned that at each reciprocation the end of the pusher 78 enters an opening 84 Figs. 1, 5, 19, in the square very near the angle of the latter, said opening being in line with the line-chamber and communicating with the same at the end where the matrices enter. In this opening lies a pusher block 85, having a finger 86 which rises through a slot in the top of the square. 7

Mounted upon the frame A of the machine (Fig. 1) is a leaf-spring 87, so arranged that as the square makes its periodical quarter-revolution, the finger 86 will, as this movement is completed, be brought directly behind the end of the spring and into contact therewith or very nearly so, as indicated in dotted lines in Fig. 5, and in full lines Fig. 16. 8 At each forward movement of the reciprocating pusher 78, its end abuts against the pushing-block 85, moving it forward against the resistance of the spring 87, thereby causing its forward end, which lies just in rear of the 9 vertical matrix-entrance to pass into the line-chamber and move the matrix standing in the said entrance into said chamber and out of the line of vertical movement followed by the matrices as they enter the line. As the 10 pusher 78 is withdrawn the pusher block is instantly snapped back to its normal position by the leaf-spring 87, leaving the entrance opening unobstructed for the descent of the 11 succeeding matrix. 1

Upon the head 73 Fig. 6, is rigidly mounted one end of an elastic strip 88 which is curved upward (Fig. 16) and then into parallelism with the line of reciprocation of the pusher 78, its end being provided with a lateral offset, or elbow, by which the straight free end 89 is brought in rear of the plane of the line-chamber, as seen in dotted lines in Fig. 5. The position and longitudinal projection of this end 89 is such that, at each forward movement it passes under and impinges upon a side lug 90, Fig. 6, mounted on the rearward, or inner face of the lower end of the line escapement lever 64, Fig. 16. This side lug stands, when the lever 64 is in its normal position, in a slightly inclined position, relatively to the line of movement of the strip 89, so that the frictional contact of the latter upon the under face of the lug 90 will vibrate the lever 64; thereby operating the line-escapement, and allowing a matrix to pass in the line-chute far enough so that one of its lower lugs rests upon the lower end 64 of the lever 64, which is pushed into one of the guides 48 Fig. 16, by the action of the straight end 89. In this position of the lever the side-lug 90 will assume a substantially horizontal position, its extended flat face resting upon the flat top of the elastic strip 89. In this 12

position the side-lug 90 cannot restore itself to its inclined position, since the elastic tension of the strip 89 is just sufficient to maintain the contact of the flat surfaces, while the restoring power of the lever spring 66 is too small to deflect the strip 89. Therefore the escapement-lever is held with its latch bolt 62 withdrawn from and its lower end thrown into the path of the matrices in one of the guides 48, until the bar 68 has completed its forward stroke, carried the end of the pusher 78 against the pusher-block 85, driven the latter forward, advanced the matrix standing in the entrance-opening of the line-chambers, and then moved back nearly to the limit of its retrograde stroke. It is not until this latter point is reached that the side-lug 90 is released by the withdrawal of the strip 89 from beneath it. As this takes place, the lever 64 snaps into its normal position, withdrawing its lower end from the guide 48 and dropping the single matrix held by said end into the entrance-opening of the line-chamber. At the same moment, the latch-bolt 62 engages the matrix directly above the one dropped, and holds the same, together with any other matrices resting upon it, until the whole operation last described is repeated. The time during which the escapement-lever 64 is held by the prolonged end 89 of the strip 88 is amply sufficient to permit the action of the pusher-block 85, by which the entrance-opening 61 is cleared, and to allow the complete withdrawal, or return of the said pusher-block 85, that it may be out of the path of the matrix which will next descend.

Within the line-chamber 51 Fig. 5, is loosely placed a follow-block or line-driver 91 preferably formed of a vertical block upon the end of a slide-plate 92 which rests upon the margins of the bottom-plate 56, Fig. 19. The end of the slide-plate 92 on which the line-driver 91 stands is next the entrance-end of the line-chamber, and in its normal position the block stands, when the first matrix enters the line-chamber 51, with its vertical face close to the entrance-opening 61, but entirely out of the path of the first matrix descending. As the pusher-block 85 advances this matrix and each matrix succeeding it in the line-chamber, the line-driver, moves step-by-step, toward the other end of the line-chamber 51, as indicated in Fig. 5, where part of a line of matrices is shown, in process of assembling. The line-driver 91 forms a support for the advancing end of the line, and its true, vertical face, against which the first matrix is driven, holds the latter and the entire matrix-series, in accurate position for casting, when the line is compressed. The line-driver is not actuated by any constantly operating force, when the line is forming, but is moved in one direction by the step-by-step movement of the matrices as the line-chamber is filled. After the type-bar is cast and the matrix-line has been carried to the point where distribution

takes place, the line-driver is returned to the position at first occupied, by devices which will be shortly described. This return-motion is for the purpose of moving the matrices back to the point of entrance, where they are removed separately for distribution. The sole appendage of the line-driver 91, for this purpose, is a stud 93, Fig. 19, which hangs from the bottom of the slide-plate 92, passing through the opening in the bottom-plate 56, and receiving a friction roll 95. The function of this device will be explained in connection with the process of distribution.

Having assembled a full line of matrices in one of the line-chambers 51, in the manner described, the next step in order is the locking-up or compression of the line, to bring it to exact column-width, in readiness for the casting of the type-bar. For this purpose the square 50 is turned one fourth of a revolution, by means hereinafter described, thereby bringing the full lines of matrices assembled into a second position, and at the same time presenting an empty line-chamber to the assembling mechanism, as clearly seen in Fig. 5.

If the mechanical details be closely compared, there may be said to be the following distinct steps necessary up to and including the injection of the melted metal within the mold; viz: first, the alignment, or the rectification of alignment, of the matrices in the line-chamber, in order that the line of intaglios may be perfectly straight; second the compression of the line longitudinally, to make it conform to the width of the column in which the type will stand; third, the moving up of the mold, including its rectified alignment with the intaglios; fourth, the rocking or vibratory movement of the melting-pot, to cause its exit-openings to register with the mold, and fifth, the injection of the melted metal.

Referring to Fig. 1, the reference-numeral 95 indicates the shaft-supporting the mold-carrier, 96. This shaft extends horizontally directly over the center of the square 50 and at some distance above it. At one end said shaft has bearing in the frame A of the machine and passes underneath the base of the column-support 14. The other end after crossing the melting-pot, receives support in a yoke-frame B, which straddles the melting-pot and is bolted to the base of the machine. The gear connections of this shaft will be explained in their proper order, hereinafter. Upon this shaft, between the melting-pot and the square 50, stands the mold-carrier consisting of a heavy disk 96, Fig. 24, having a sleeve 97 upon its rearward face by which it is loosely mounted upon the shaft.

At four separate points upon the mold-carrier, having their centers separated by equal intervals of ninety degrees of arc, are the separate mold-casings 98, Fig. 23. The mold casings are so constructed and arranged as to project in front of that vertical face of the disk 96 which lies adjacent to the

square. The mold-casings consist of oblong, rectangular bodies of metal of somewhat less length than the side of the square (Fig. 5) and have a projecting rectangular lip 99 Figs. 23, 24, in front and a similar lip in rear. The molds 100 are formed in the central, longitudinal line of these lips and are open in front and in rear. They are preferably made adjustable, as to the length of the mold, by the employment of longer or shorter end pieces 101. If a mold is to be shortened longer end pieces are employed, and if the mold is to be lengthened then shorter end pieces are used. The mold-carrier or disk 96, being simply sleeved upon the shaft 95, without key, or spline, is moved with said shaft only at stated intervals and is also movable thereon without revolution toward and from the square, to enable the mold in which the cast is to be made to close upon the line of matrices and then move away to permit the square to make its periodical quarter-turn without striking the mold-casings 98. During this turn of the square, the mold-carrier must have a quarter of a complete revolution to bring another mold around to the next line of matrices. The movement of the mold-carrier last described is made by the agency of a spring 102 coiled around the shaft 95 between the end of the sleeve-bearing 97 and a cam-block 103, rigidly mounted on the shaft 95 near the yoke-frame B. The separation of the mold from the matrices and the movement of the mold-carrier by which it is effected, are brought about in the following manner.

Loosely mounted upon the shaft 95 is a cam-ring 104, 23^a, 24, lying between the mold-carrier 96 and a bevel-gear 105 keyed on the shaft near the front, or inner vertical face of the mold-carrier. Upon the flat face of the cam-ring 104 is a cam-segment 104^a and upon the adjacent flat face of the bevel-gear 105 is a cam-projection 105^a of suitable form to engage the cam-segment 104^a at each revolution of the shaft 95. Evidently, the mold after receiving the casting, must move away from the matrix-line at least an instant before the rotary movement of the square can begin. Moreover, as the latter is horizontal and the mold-carrier vertical and as both must accomplish a quarter-revolution before another type-bar can be cast, provision must be made for effecting these movements without collision between the angles, or angular portions. For this purpose the cam-ring 104 is unsupported on the shaft 95, but is prevented from revolving therewith by a bar 106 projecting from one side of the cam-ring and having its end pivoted, or suitably attached to a rigid support 107, Fig. 27, in such manner as to permit the slight movement of the cam-ring under the push of the cam-projection 105^a. By this operation of the cam, the mold-support 96 is driven slightly away from the square and brought into such position as to enable the lock-connection to operate whereby it is caused to partake of the revolution of the

shaft 95, and this rotary movement of the mold-carrier is begun at such time, relatively to the movement of the square, that the angle or corner of the latter has ample space to make its movement in the opening, or space, between the adjacent ends of two of the mold-casings and the edge of the disk, or mold-carrier, as best seen in Fig. 23. The movement of the square being completed just before that of the mold-carrier, the mold-casing 98 can turn without obstruction into parallelism with the adjacent face of the square. The cam 105^a, Fig. 24, on the bevel-gear 105, is timed to pass off the cam-segment 104^a on the face of the cam-ring 104 just before the rotary movement of the latter is arrested, thereby permitting the spring 102 to drive the mold-carrier toward the square at the close of its quarter-turn upon the shaft 95.

Upon the front face of the mold-carrier 96 are rigidly mounted four rules 108, each having a straight edge 109, parallel with the longitudinal line of the adjacent mold. These rules are arranged around the shaft 95, but at some distance therefrom, being so located that, when the mold closes upon the matrix-line, the rule 108, parallel therewith, will overlie and have edge-contact with the surface of a table 110 (Figs. 1, 2 and 24) which projects from the A frame and passes between the square and the shaft 95. The upper edge of this table is accurately parallel with the line of intaglios, when the matrix-line lies in position for casting. Each rule 108 is so placed that, as the mold-carrier moves up and brings the mold against the line of matrices, the straight edge 109 will seat upon the top of the table, at the edge thereof, and not only act as a stop for the mold-carrier but will also align the mold 100 so that it will coincide with the lines of intaglios. Moreover, as the mold-support moves up toward the line of matrices, a moment before its rotary movement is completed, the flat, front face of the rule 108 is caused to abut against the edge of the table 110, until the mold carrier 96 rotates sufficiently to place the straight edge 109 of the rule 108 in the proper position, or parallel with the top of the table, whereupon the spring 102 moves the mold-carrier and the straight edge of the said rule will snap over the top of the table a distance nearly equal to the thickness of the rule, thereby arresting the movement of the mold-carrier and at the same time bringing the central longitudinal line, of the mold 100 into alignment with the corresponding line of the intaglios. While the movement of the mold-support last described brings one of the molds 100 up to the line of matrices and carries its lip 99 through the opening 58 in the plate 54 and against the edges of the matrices, no sufficient pressure is yet exerted to press the said parts together to form a close joint, the tension of the spring 102 being inadequate for this purpose. As the mold closes up to the line in the manner described, the matrices are ad-

justed, or rectified, by a presser 112, Fig. 24, lying in a slot in the table and having a lower edge, which is preferably straight, overhanging the lugs which project from the upper ends 5 of the matrices toward the mold. Normally, this presser is raised sufficiently to clear the matrices, as the square turns, by means of a spring 113, Fig. 25, underlying a flange or rib 114, on its upper edge, the ends of the spring 10 lying in shallow seats in the table 110. At the proper moment the presser is thrown down by a spring-cam 115 composed of an elastic plate fastened at one end to the periphery of a raised annular face 116 upon the 15 flat face of the bevel gear 105. This spring-cam acts upon a friction-roll 117, journaled upon the top of the presser, said cam having a concentric continuation, or riding-face, long enough to hold the presser down and cause 20 it to bear upon the matrices until the operation of casting is completed. Said presser 112 is limited in its upward movement by a pin 112^a on its face, moving in a slot in the edge of the table 110.

25 The quarter-turn of the mold-carrier 96 is produced by the revolution of the shaft 95, in the following manner: Upon said shaft close to the yoke-frame B Fig. 24, in which it has bearing, is mounted the cam-block 103, 30 which carries a housing 118, projecting toward the mold-support and containing a clutch-bolt 119 and a spring 120, by which the clutch-bolt is normally drawn away from the mold-carrier, and into the housing. On the 35 vertical face of the bearing in the yoke-frame B is formed a raised-cam-segment 121, (Figs. 24 and 26) having an inclined end 122 lying next to the end of the clutch-bolt 119, which projects from its housing to, or nearly to the 40 face of the bearing B. As the shaft 95 begins to turn, carrying the cam-block 103 with it, the end of the clutch-bolt 119 is caused to ride upon the inclined end 122 of the cam-segment 121, thereby driving the clutch-bolt 45 toward the mold-support and compressing its retracting-spring 120. The mold-support being, at or about the same instant, moved toward the cam-block by the action of the cam-segment 104^a and cam 105^a, the end of its 50 sleeve bearing 97 passes the projected end of the clutch-bolt and the latter is caused to engage with one of four spurs, 123, Figs. 1, 2, 24, which project from the end of the sleeve 97 nearly in radial lines. These spurs stand at 55 equal intervals of separation and are located, when the mold-support is at rest, substantially as shown in Fig. 4. In this position, the lowermost spur is a little in advance of the point of the clutch-bolt 119, whereby opportunity is given to the latter to make the movement by which it is projected, and time is also given for the mold-support to draw off from the matrices, both these movements being made after the shaft 95 begins its periodical 60 revolution and before the clutch-bolt 119 engages the lowermost spur 123. As the shaft

makes one full revolution at each quarter-turn of the mold-support and square, the cam-segment 121 (Fig. 26) is of such length that it will maintain the engagement of the clutch-bolt 119 and the spur 123 long enough, only, to accomplish the quarter-turn to be given to the mold-support. The clutch-bolt then rides off the cam-segment 121, and the mold-support is released and moves up again toward 70 the square, while the shaft continues its movement until its revolution is completed and the clutch-bolt 119 brought back to its point of rest, closely adjacent to the inclined end 122 of the cam-segment, in readiness for a second 75 operation repeating the several movements described. The several gear-connections by which these movements are produced, and the arrangement of the same, will all be explained 80 in due course.

85 In the description of functions attending, or preparatory to the filling of the mold with melted metal I have made no mention of the mechanism by which the line is compressed to bring its length to the exact width of the 90 column in which it is to stand. It is well understood, in this art, that in assembling the line of matrices, the exigencies of orthography and the division of words running over into the next line, render it necessary that a certain latitude of excess in the length of the 95 line shall be compatible with a subsequent compression by which its length shall be reduced to the standard. I easily accomplish this object by employing elastic spacers, of 100 the kind shown in United States Letters Patent No. 470,649, granted me, jointly with L. G. Hine, assignee of a half interest therein, upon the 8th day of March, 1892. These devices and others for similar purposes are so 105 well known as to require no explanation.

110 The line-compressor consists of a strong but suitably elastic bar 125, (Fig. 4,) having its lower end mounted on a bracket 126, which is rigid with a rock-shaft 127, the bearing for 115 the latter being in the upper end of an upright 128, arranged at the front of the machine and at the left hand of the operator as he stands at the key-board. From the point of its attachment the bar 125 extends upward 120 and is then bent over so that its end points toward the line of matrices on which it acts. The bar is provided with a widened portion 125 which has a slot 129 Fig. 1, to permit it to pass a shaft which stands in its path. Until brought into action, the compressor is drawn 130 somewhat toward the front, whereby the extremity is removed from the path of the angle of the square as the latter makes its periodic quarter-revolution. The end 130 Fig. 5, of the compressor is reduced in width to enable it to enter the opening in which the pusher-block 85 lies and drive the latter forward until its pin 86 reaches the end of the slot 87^a, which provides a stop therefor, thus bringing 135 every line of matrices to the same length. During the moment occupied in filling the

mold with melted metal the line of matrices is maintained under pressure, by the means last described.

The line-compressor is operated, by means 5 of a lever 131, Figs. 1 and 4, rigidly connected to the rock-shaft 127. Said lever extends below the rock-shaft for some distance and its lower end is pivotally connected to a slide 132, arranged in a chamber in the upright 128, in 10 which the slide is capable of movement toward and from the front of the machine. The connection between the lower end of the lever and the slide is by means of a strong pin, or stud 133 which passes through a slot in the 15 wall of the chamber inclosing the slide. The outward movement of the slide 132, by which the line-compressor 125 is operated, is produced by one of a series of four cams upon the vertical shaft 60, which forms a bearing for the 20 sleeve 59 on which the square is carried. The opposite movement of the parts, by which the line-compressor 125 is drawn away and the matrix-line released, is produced by a spring 134 Fig. 4, connected by one end to a lever- 25 arm 135 on the rock-shaft 127 and at the other end to a pin 136, Fig. 1, which projects from the upright 128.

As the construction, arrangement and operation of the line-compressor and the parts by 30 which its action is produced are substantially the same as the corresponding parts shown and described in the Letters Patent granted to myself and L. G. Hine, assignee of one-half interest, upon the 30th day of August, 1892, 35 No. 481,920, further description thereof would seem unnecessary. As the cam on the vertical shaft 60, by which the slide 132 is operated, is one of a series of cams having a serial action, it will be referred to hereinafter 40 in its proper order.

Having now aligned the matrices, compressed the line and brought the mold up to it, with its lip 99 entering the front of the line-chamber and resting against the edges of 45 the matrices, it is necessary to fill the mold with melted metal and for this purpose the mold must be momentarily pressed against the matrices to form a close joint. The spout of the melting-pot must also, be brought into 50 communication with the mold and the fluid metal driven therein. To these ends I provide a melting-pot 137, Figs. 30, 31, preferably of cylindrical form, or nearly so, and enclosed by an outer jacket 138, which extends 55 far enough below the bottom of the pot to form a combustion-chamber 139, which communicates with a spiral passage, or passages, 140, one or more, formed in the annular space between the inner and outer walls 137 and 60 138. Within the inner wall 137, upon one side, is arranged the vertical exit passage, 141 for the metal which passage at its upper end is curved across the spiral channel 140, and extended through the wall of the outer jacket 65 138. In the latter is formed an elongated, transverse seat having a concave face upon which rests an elongated spout 142, having a

convex face fitting the seat, against which it is held by suitable means, such, for example, as cone-bearings 143, adjustable in lugs 144 7c at the ends of the seat, whereby, as the axes of the cone-bearings are concentric with the curvature of said seat as well as the convex face of the spout 142, the latter can readily adjust itself within the former in such manner as to bring its outer flat face against the open side of the mold and make a close joint therewith as shown in Fig. 30, where the mold is indicated by dotted lines. A series of exit openings 145 is formed in the spout, 80 their mouths being preferably diminished in size, as seen in Fig. 30. The preferred fuel is gas, which is introduced through a pipe 146, to supply a plurality of burners 147 of any suitable type, air being obtained through 85 openings 147a in the bottom of the chamber 139. The products of combustion traverse the spiral channel 140 and pass off at the upper end thereof, through any suitable form of flue, the latter being shown in dotted lines 90 in Fig. 31. This construction insures a complete consumption and utilization of the products of the primary combustion and also provides simple and adequate means for preserving a suitable temperature in the exit- 95 channel, or passage 141 and especially in the upper portion thereof, where the melted metal might, otherwise, be in danger of chilling.

The melting-pot is provided at its lower end with two depending brackets 148 on opposite sides. These brackets are pivotally connected to adjustable supports, each consisting of a thick plate 149 Fig. 32, set in a dovetailed channel in the inner face of one of the upright members of the yoke-frame B 10 Fig. 1. From the inner faces of these plates 149 Fig. 32, project thimble bearings 150 supporting an axis 151, Fig. 1, rigidly fixed in the thimbles and passing loosely through openings 152 Fig. 30, in the depending brackets 148. At the other ends of the supports 149 are bosses 153, Fig. 32, which receive the ends of the bolts 154, Fig. 1, which extend through openings in lugs 155, upon the yoke-frame B, their threaded ends receiving nuts 11 156, by which the pivotal axis of the pot may be very accurately adjusted, until an exact register is secured between the spout and the mold, by rocking the melting-pot upon its pivotal support. This movement of the melting- 12 pot is timed to take place as soon as the line is compressed. It is produced by cams 157 (Figs. 1, 2, and 30) rigidly mounted upon a shaft 158 which has its bearings in extension- 13 arms 159 upon the members of the yoke-frame B. These cams 157 lie upon one side of two vertical arms 160 Fig. 30, which rise from the top of the pot upon the side most remote from the mold. These arms are separated from each other by an interval nearly equal to the 14 diameter of the pot. They have a considerable rigidity, to enable the cams to exert proper force in pressing the spout 142 against the mold, but they are elastic in a sufficient

degree to enable them to yield slightly, should this be necessary, and thus avoid injury to the mechanism. As the strain falls almost entirely upon these arms 160, they are provided at their ends with friction-rolls 161, which ride upon the cam-faces. Upon the opposite side of the cam-shaft 158 lie arms 162 which rise from the points on the pot where the arms 160 are mounted and curve beneath the shaft 158 and then extend upward. These arms have no other function than to draw the melting-pot away from the mold and restore it to the position it occupies during the casting operations.

15 Within the melting-pot 137, is arranged a heavy piston 163, having a lift-bar, or rod, 164, pivotally connected to it and to a frame consisting of a bar 165, Fig. 31, lying parallel, or in a plane substantially parallel with the shaft 158, said bar extending toward the rear of the machine and to some distance from the top of the melting-pot, where the end of the bar is pivotally attached to an upwardly extended arm which forms part of a rigid bracket 166, 25 extending from the pot toward the rear of the machine.

Upon the lift-bar 165 is formed a rigid elbow-arm 167, which rises from a point over the rear side of the melting-pot, and at a suitable point above the lift-bar bent into substantial parallelism with the said lift-bar, its point resting upon the periphery of the cam-block 103 on the shaft 95. This cam-block is provided with a pocket 169, formed by cutting into and removing a portion of said block, the pocket being formed with a straight side 170 and an inclined side 171.

The direction of movement of the shaft 195 is indicated in Fig. 31 by an arrow, from 40 which it will be seen that, as the cam-block 103 turns, the point of the elbow-arm rides upon its periphery until the pocket comes around whereupon the point of the elbow-arm 167 rides over the edge of the straight side 170, thus releasing the lift-bar suddenly and allowing the piston to fall. Its force is aided, if necessary, by a spring 172 connected to the lift-bar 165 and to a lug 173 projecting from the outer jacket 138 of the pot.

50 The force of the weighted piston drives the melted metal up the passage 141 and through the spout and dashes it into the mold filling the same almost instantaneously and forming a type-bar having a proper type-face. The type-bar being thus formed it remains in the mold for the time being, or until the mold-support has made three successive quarter-turns, thereby bringing the type-bar, still lying in the mold, to a point at the left-hand 55 of the key-board (Fig. 2) where it is discharged from the mold upon the table 110, as will be presently explained. As the mold draws off from the matrices, the melting-pot is rocked by the cams 157 and its spout 142 is drawn away from the mold, which is turned through one-fourth of its circle of complete revolution. As this turning movement takes

place, the rearward lip 99 of the mold, against which the spout of the melting-pot was brought, is carried in close contact with a planing tool 174, (Figs. 2, 4, 29) mounted upon an extension-arm 175, arranged beneath and transversely to the shaft 95, one end of said arm being supported by the front of the table 110 and the other end by a strong upright 70 176, Fig. 4, the lower end of which rests upon the base of the machine. The planer is adjustable upon its support by means of slots 177 Figs. 2, 29, in its base-piece which receives the attaching bolts. A second and more delicate adjustment is provided by means of set bolts 178, tapped through the supporting-plate and resting against the inner face of the planing-tool, whereby the edge of the tool may be adjusted toward and from the mold. 80 As the latter makes its first quarter-turn, after receiving the cast, the rearward lip 99 of the mold is drawn over the edge of the planer and any metal projecting from the open mold is shaved off, making the base of the type-bar 90 smooth and of such accurate form that when resting upon said base the printing-face of the bar will be type-high.

In separating the spout 142 from the mold it is unavoidable that there should be nipples, or nodules, which will protrude from the open side of the mold. The exit-openings in the spout being small compared with the width of the mold, and the metal in the spout being fluid, or very nearly so, enough will be drawn out in small nipples by the removal of the spout to necessitate the planing, or trimming off of the base. The trimming of the base of the type-bar being effected in the manner set forth, during the first quarter-turn of the mold-carrier, subsequently to the operation of casting, two succeeding quarter-turns are made before the type-bar is ejected from the mold in which it was cast, during which the casting has some opportunity to cool. Upon the third and last of these periodic movements, the mold reaches the position shown in Fig. 2 at the lower side of the figure, and in Figs. 1 and 4 at the left-hand and right-hand sides, respectively. At this point the longitudinal line of the mold is vertical and lies in the same plane with an ejector 179, which consists of a plate of less thickness than the type-bar. The end of this plate is supported in a guide-bracket 180, mounted on the extension arm 175. It is reciprocated by a bar 181, to one end of which it is riveted, or bolted, and at its other end a guide-bar 182 is attached, sliding in a supporting bracket 183. Reciprocation is imparted by a wrist pin 184 projecting from the face of a disk 185 which is carried upon the front end of the shaft 158.

At the right-hand of the mold as it stands in the position last mentioned, and close to the lip 99 in which the type-edge of the bar lies, are arranged milling-rolls 186, Fig. 28, mounted on vertical shafts which have bearing in an upright frame 187, which rises from

the front of the table 110. The milling-rolls are geared together at the top by spur-gears 188, and are rendered adjustable by upper and lower set-screws 189, to bring their adjacent faces accurately into such position as to enable them to operate equally upon both flat faces of the type-bar as it passes out of the mold under the impulse of the ejector 179. The shaft 190 of one of the milling-rolls (Fig. 28) is extended downward through the table 110, to a lower table 191, Fig. 4, upon which its end is stepped, and there receives a bevel-gear 192, through which said shaft has revolution by gearing which will be described at the proper point. The milling-rolls revolve at a high speed whereby the two flat faces of the type-bar are dressed off smoothly and the type-bar is left in condition to be set up in the proof-galley. The ejector plate 179 Fig. 2 is so thin that it passes between the milling-rolls without contact and carries the type-bar entirely clear of the same. The milling-rolls may be rotated in either direction desired. As the bar passes out between the milling-rolls, its lower end is received upon ways, or rails, 193, (Figs. 2 and 28) and is immediately thrust by a stacker 194 toward the front of the machine. The stacker 194 consists simply of a block of trapezoidal form, its abutting face, being so inclined as to tilt the type-bar into an inclined position, as shown in Fig. 28, whereby it must fall in an inclined position against a stacking-plate 195, which is movable upon the rails 193. The first type-bar rests on this inclined stacking plate and as the succeeding type-bars are thrust from the molds they accumulate in a series, each lying at the same angle upon the preceding type-bar, the whole stack being within sight and easy reach of the operator, or his assistant. The stacker is reciprocated by an arm or pitman, 196, which derives its reciprocation from an eccentric 197 Fig. 27, upon the shaft 95. The end of the pitman 196 has pivotal connection with a bracket 198 having a foot, or base, which is guided between the rails 193 Fig. 2. The stacking devices and milling-rolls are all mounted upon a support which is fastened to the table 110 Fig. 27, by bolts 199. The stacker reciprocates through a slot, or opening 200, Fig. 28, in a vertical plate 201, which prevents the type-bars from accidentally toppling over in the wrong direction, after they pass between the milling-rolls.

Having now assembled a line of matrices and cast a type bar therefrom, the last step remaining in the order of operation is the removal of the matrices one-by-one from the line-chamber and their return to their proper cells of the magazine, in order that a sufficient supply may be present, in all the cells, at all times, so long as the mechanism is in operation. If the same line of matrices assembled in one of the line-chambers of the square, as described at a previous point in this specification, be followed throughout as it has thus far been followed, it will be seen from Fig. 5

that the removal of the matrices and their distribution take place after the square 50 has made its third quarter-revolution. In 70 this final procedure there are several minor, or subordinate steps which are as follows: The matrices forming the line are removed from the line-chamber individually and through the same opening 61, Fig. 19, by which 75 they were introduced when first assembled. For the purpose of removal by this opening, the whole line must be driven step-by-step, toward the end of the line-chamber in which 80 said entrance-opening 61 is formed, and automatic means must be employed to effect their ejection singly, in such manner that they may pass to the left and be carried to the upper end of the magazine where they are automatically delivered to the distributing devices. I will explain these operations, therefore, in their order. The feed of the line whereby the matrices are brought successively into the entrance opening 61, is effected by a line-driver 202, (Fig. 5,) one end of which 85 is supported upon a pivot 203 Fig. 2, at the rear of the machine. The pivotal support is sustained by an arm 204, (Fig. 18) bolted to the machine frame. Connected to the pivotally mounted end of the driver 202 is a 90 drum 205 (Fig. 2) containing a coiled spring 206, the tension of which is exerted upon the line-driver in such manner as to sweep its free end normally in a direction opposite to the movement of the line of the matrices, as 95 said line is turned into position for distribution. The end of the driver extends in a horizontal plane, or nearly so, just beneath the square, and lies, when at rest, in such position that as the square makes its third quarter-turn, the friction-roll 94 Fig. 5, impinges upon the end portion of the said driver and turns it upon its pivotal axis 203, Fig. 2, thereby 100 putting the spring 206 under increased tension. When the third periodic movement of 105 the square ceases, the driver 202 will have been turned to the extreme right hand end of the line of matrices, (regarding Fig. 5 as the basis of explanation,) and will, in that position exert its force upon the follow-block 91, 110 by pushing it toward the entrance-end of the line-chamber as fast as the removal of the matrices will permit. This function is illustrated in Fig. 5, where all but seven matrices 115 have been ejected from the line chamber and the line-driver 202 is shown still pressing the follow-block 91 forward to feed these remaining matrices up to the entrance-opening 61.

Referring now to Fig. 19 the reference-number 207 indicates a bracket attached to the under surface of the square beneath, and substantially in line with the opening in which lies the pusher-block 85. In a suitable recess in said bracket is journaled a spur-gear 208, upon the shaft 209, which is impelled in 125 one direction by a spring 210 (Fig. 4) coiled upon it. With the spur-gear 208 Fig. 19, a rack of teeth 212 has mesh, said rack forming part of a vertical bar 213, which lies in a

dovetailed recess in the bracket 207. Shown also in dotted lines in Fig. 5. This bar 213 Fig. 19, is capable of rising till its upper end is as high as the bottom of the pusher-block 85, and by its rise it revolves the spur-gear 208 and increases the tension of the spring 210, whereby the bar is shot down as soon as the device by which it is raised is removed from beneath it. It will be noted in Fig. 19 5 that the upper end of said bar is arranged just in rear of the entrance-opening 61 in the line-chamber, and its normal position under the impulse of the spur-gear 208 is with its end just beneath the bottom of the square. Upon the front of said bar 213 is mounted a leaf spring or elastic plate 214 having its lower end attached to the lower end of the bar by a thin block 214^a, which also serves as a stop or limit to the upward movement of the bar 20 214. This elastic plate is co-extensive with the length of the bar, or substantially so, and upon its upper end is mounted the ejector-head 215, secured to the front face of the plate and flush with its end, or nearly so. In front of the elastic plate 214 is a keeper 216 which may form part of the bracket 207, and which lies so close to the front face of the plate 214 that the latter is pressed back against, or nearly against the bar 213. In 25 this position the block 215 projects beneath the entrance-opening 61 just far enough to insure its engagement with the lower end of the single matrix lying in said entrance-opening. As the bar 213 is driven upward by the means hereinafter named, the normal tension of the elastic plate 214 impels it to advance the block 215 under the end of the matrix, the purpose being to maintain the engagement with the end of the matrix. The moment the 30 latter rises even a small fraction of an inch, all danger of the ejector-head 215 catching and ejecting the contiguous matrix is wholly avoided, and should the elastic force of the plate 214 throw the head 215 forward, it will merely strike against the plain rear face of the second matrix and slip thereon. As the matrices vary in thickness according to the alphabetical width of the letter-intaglios, it is evident that the thickness of the head 215 actually 35 lying beneath the entrance-opening must not exceed the thickness of the thinnest matrix and preferably it is even a little less, in order that no danger may be incurred of driving out two matrices simultaneously. The parts last described form a portion of the matrix-ejecting-mechanism, and are permanent adjuncts of the square, said parts being duplicated for each of the four line-chambers. The spur-gear 208 and ejector-bar 213, with 40 the elastic plate 214 attached, are carried upon and with the square at each of its periodic revolutions. At each stop of the square, after completing one of its periodic quarter-turns one of the ejector-bars 213 is brought directly over a vertical bolt, or bar 217 mounted in a carrier 218 (Figs. 4 and 19) which lies in guide-ways in the machine-frame. The

lower end of the bolt 217 is set in a slot, or notch, in the upper edge of the carrier 218 (see Figs. 4 and 19) and is mounted upon a pivot 220, its lower extremity being cut squarely below the pivot to prevent its turning thereon toward the right-hand of the machine, but being rounded on one angle to permit it to turn in the opposite direction. Upon that face of the bolt 217 which terminates below in the rounded angle, is mounted a leaf-spring 221, extending downward below the end of the bolt and resting upon the outer face of the carrier 218. The tension of this 45 spring maintains the vertical position of the bolt as shown in Fig. 19, but permits it to turn upon its pivot 220, against the impulse of the spring 221, in case the hanging end of the ejector-bar 213 should, by any chance, 50 come in contact with the upper end of the said bolt during the quarter-turn of the square. Such contact is not likely to occur, but is not impossible. Should it occur, the bolt 217 merely yields and permits the ejector-bar to pass, vertical position being immediately restored by the spring 221. The carrier 218 is reciprocated by an eccentric 222, carried by a short shaft 223, which has its bearing in a bracket 224, bolted to the rearward face of an upright, rectangular portion 225 of the machine-frame which rises from and forms part of the table 191, arranged (Figs. 1, 4 and 18) in a plane just above the top of the upright 128. This table is formed in two parts, one of which projects from the inner face of the A frame. The line of division between the two parts of the table passes from front to rear and through the center of the rectangular portion 225, Fig. 18, which forms a housing, or inclosure, for the vertical shaft 60. Upon the meeting edges of the parts forming said table are strong flanges 227, which receive uniting bolts 228. Upon the outer, or left-hand end of the short shaft 223 Fig. 19, is a bevel-gear 229, to which revolution is given in the manner hereinafter pointed out, the whole system of actuating gearing being described separately. As the matrices are separately driven upward in the entrance-opening 61, 55 Fig. 19, by the action of the ejecting-mechanism, the laterally projecting lugs at their upper ends enter a lift-guide 230 (see Figs. 4 and 5) the lower end of which lies directly over the inner side of the entrance-opening 61. This lift-guide consists of a simple channel or trough inclosed upon three sides, and of such interior dimensions as to receive and permit the free movement of the lugs of the matrices. The opposite or outer side of the 60 entrance opening 61 is overhung by the lower end of a cylindrical drum 231 in the wall of which is formed a slot, or channel 232, of a width capable of receiving the lugs upon the outer edges of the matrices. Within the drum 231, which is rigidly secured in place, is arranged a cylinder 233 having a spiral lift 65 234 formed upon its surface at a suitable pitch. The exterior diameter of the cylinder

233 as compared with the interior diameter of the drum 231, is such as to leave an annular space 235 between the two, of such width that the distance from the face of the cylinder 233 to the closed vertical side of the lift-guide 230 shall but little exceed the outside measurement of a matrix, from the end of one of its side lugs to the end of the lug transversely opposite. In the thicker matrices this condition is of less importance because the lugs are, in all cases, of the same thickness and this is equal to the thickness of the thinnest matrices. In the thicker matrices, therefore, the longitudinal shoulders formed by the thick body-portions will abut against the exterior faces of the drum 231, as shown in Fig. 5, at the upper left-hand part of the said figure. Those matrices, however, which are of the same thickness as their lugs are capable of entering bodily within the slot 232, and to guard against the escape of the lugs from the lift-guide 230, the width of the channel traversed by the lugs and bounded on one side by the face of the cylinder 233 and on the other by the closed side of the guide 230, is made to correspond with the maximum width of the entrance-opening 61 in the line-chamber. The spiral 234 is continued to the extreme lower end of the cylinder 233, where its extremity passes off at the same uniform pitch. The end of said cylinder and the point where the thread disappears is just below the point where the lower edge of the upper, outside lug of the matrix will stand, after the ejector has driven the matrix upward to the full extent of its stroke. Thus, as the cylinder 233 revolves the lower terminal of the spiral 234 will pass under said lug and as the cylinder continues its revolution the matrix will be drawn up in the slot 232 and in the lift-guide 230, as seen in Fig. 4. As one matrix is thus taken from the line-chamber, those still remaining therein are advanced a single step by the pressure of the line-driver 202 bringing another matrix into the entrance-opening 61, ready to be driven upward by the next action of the ejector. It should be noted, however, that the stroke of the latter is such that each matrix is raised somewhat less than half its length, and that until the spiral lift 234, has carried said matrix entirely out of the line of matrices, there can be no advance of those matrices still remaining in the line-chamber. Therefore a succeeding matrix cannot be moved into position to be engaged by the ejector until its predecessor has traveled a given distance upward upon the spiral lift 234. This function is very clearly shown in Fig. 4. The drum 231 is rigidly supported at its upper end by an extension-cap 236 (Figs. 3 and 11) which is bolted to the exterior cap-plate 237 of the magazine. At its lower end the drum is sustained by suitable collars 238, Fig. 4, or other suitable means. The lift-guide 230 is still further strengthened by a collar 239 (Figs. 11, 12) embracing the drum 231, and having parallel arms 240 which

extend to and around the lift-guide at a point between its ends. The lift-cylinder 233 Fig. 11, is preferably hollow its ends being closed by 70 perforated plugs 241, the upper end-plug being inserted a little below the open top of the cylinder to form a cupped space suitable for catching the oil used upon the bearings and allowing it to percolate through the apertures 75 in the plug 241 and pass down inside the cylinder, thus preventing the oil and grease from becoming smeared upon the matrices. The lift-guide 230 extends upward, enters the outer jacket or envelope, 4 of the magazine (Fig. 11) 80 and passes upward in the annular space between the inner and outer shells 3 and 4. Its upper extremity lies in a slot in the face of the outer shell, at the top of the latter, as shown in Fig. 9. This point lies in a line joining the 85 center of the magazine and the center of the lift-cylinder and to reach it the lift-guide 230 is curved, or "skewed," through an arc of about forty-five degrees, more or less, said curvature being shown in Fig. 1, and being 90 concentric with the lift-cylinder. The purpose of this arrangement is to bring the matrix, as it arrives at the top of the lift-guide 230 into such a position that it will lie directly across the annular space between the inner 95 and outer shells 3 and 4 of the magazine, or in other words, in the radial line of said magazine. For the same reason, the slot 232 in the drum 231, travels, in rising to the top, through a concentric arc of less radius. The 100 lift-cylinder 233 is revolved continuously within the inclosing drum 231 by its vertical shaft 242, Fig. 11, which extends below the lower end of the lift-cylinder and is supported by a bracket 243, Fig. 4, which forms part of 105 the bracket 224 Fig. 18. Upon the end of said shaft below the bracket 243, Fig. 4, is a bevel-gear 244, driven by means hereinafter explained. The revolution of the lift-cylinder causes the foot of the spiral 234 to engage 110 beneath the upper and outer lug of the matrix and carry the latter steadily upward in the slot 232 and lift-guide 230. The pitch of the spiral 234 is such that the distance between successive convolutions is a little in 115 excess of the distance between the bottom of the upper lug and the bottom of the lower lug on the matrix. The spiral 234 terminates at a point below the upper end of the lift-cylinder (Fig. 11) and at its upper terminal 120 it is brought, upon its upper and engaging face, into parallelism with the plane of rotation. As the upper lug on the matrix passes off this terminal the next succeeding convolution of the spiral impinges upon the bottom 125 of the lower lug and pushes the matrix upward until its top arrives at the upper end of the lift-guide 230, which is the limit of upward movement. Having arrived at this point, the lower lug of the matrix rides for a 130 moment upon the horizontal surface 245, Fig. 11, of the terminal of the spiral 234, whereby it is held, or sustained, for a brief period during which it must be engaged with and driven

upon the distribution-bar. For this purpose I provide a wheel-carrier (Figs. 3, 8 and 11) consisting of a central hub 246, having radiating spokes 247 uniting the hub with a concentric rim 248. The hub 246 is loose upon the upper part of the fixed axis 6 of the magazine, and extends downward sufficiently to rest upon the rigid collar 7, and in the opposite direction it is provided with a sleeve-extension 249, which passes upward through the upper cap 237, between the same and the fixed axis 6, and rises above the cap far enough to receive a worm gear, 250, which is keyed or otherwise fastened upon the sleeve-extension 249. The worm-gear 250 has mesh with a worm 251 upon a shaft 252, journaled in bearings 253 (Fig. 2) upon the upper cap 237. The shaft 242 of the lift-cylinder is prolonged upward (Figs. 2, 3 and 11) through the extension-cap 236 and on its projecting end is provided with a bevel gear 254, which meshes with a similar bevel-gear 255 upon the end of the worm-shaft 252. By this arrangement the rotation given the shaft 242 of the lift-cylinder is imparted to the wheel-carrier through the medium of the worm-gear and shaft. The circular rim 248, Fig. 11, of the wheel-carrier lies just within the top of the inner shell 3 of the magazine, its upper horizontal face being slightly above the edge of the shell. Upon this horizontal face is attached an annular plate 256, Fig. 8, having a radial series of carrier-fingers 257, which extend over the edge of the inner shell 3, Fig. 11, and are bent, or otherwise formed, to approximate the shape of a letter V. This V-shaped portion lies within the annular space between the inner and outer shells 3 and 4 of the magazine, the two downwardly converging parts of each carrier-finger 257 being in line, or nearly so, with the sides of the V-shaped notch or opening in the upper end of each matrix in which notch the combination is formed by which the distribution is controlled. The several parts of the mechanism are so timed and arranged that the upper end of the matrices, as they are lifted by the spiral 234, will enter between the carrier-fingers 257 at, or about, the moment the lower lugs of the matrices pass upon the horizontal face 245 of the upper terminal of the spiral 234. Resting here without motion during the short time in which the said horizontal face 245 passes beneath the matrix, the carrier-finger 257 in rear of the matrix is brought against the latter and carries it in a horizontal plane and in the circular line of movement within the upper end of the annular space between the inner and outer shells 3 and 4, in which the shells are arranged. Mounted upon the upper cap 237, directly over the top of this annular space, is the circular distribution bar 258, having a form, in cross-section, corresponding with the shape of the combination notches in the upper ends of the matrices, the two converging faces of the bar being provided with ribs having an arrangement corresponding with the

several permutations of the hooks, or points, in the notches of the matrices. The end of the circular bar 258 lies at such a point that the matrix, when lifted to its upward limit of movement lies close to said end and in position to ride upon the bar by an extremely limited movement which is made in the direction of rotation of the horizontal terminal portion 245 of the spiral which thus moves with the matrix as it is advanced upon the end of the distribution-bar by the fingers and insures its support until it has been securely engaged with the ribs upon which it will move until it arrives over the cell in which it properly belongs. The initial end of the distribution bar, which enters the notch of the matrix as the latter receives its first impulse from the carrier-finger is preferably plain-faced, or denuded of its ribs, for a very short space, to facilitate the passage of the end of the bar into the notch of the matrix without difficulty. Being placed upon the bar in this manner the matrices are caused to traverse the same by the finger-carriers, which lie immediately beneath the converging faces of said bar and substantially conform thereto in angular inclination. These fingers thus act upon the matrices at the points of maximum frictional resistance and insure their easy, uniform and accurate movement without materially deflecting them from their normal, vertical position. As they traverse the distribution-bar the inner lugs upon their lower ends move in the channel or passage 17, (Fig. 17,) and the upper lug upon the same side rides just above and out of contact with the points of the oppositely beveled projections 18. Upon reaching the point where an individual combination ceases and where a matrix having an identical combination will leave the distribution-bar, and as it drops by gravity, the oppositely beveled ends of the projections 18 act as a guide to the lug on the upper end and inside edge of the matrix, while the same office is performed for the lower lug upon the same side, by the similarly beveled ends of the portions 16, lying between the cells 15. The construction last described is duplicated upon the inner face of the outer shell 4 of the magazine, to guide the lugs of the matrix on the outer edge thereof. This construction is simple but is of marked efficiency in making a rapid and accurate distribution of the matrices. With a moderate speed of movement upon the circular distribution-bar, the momentum of a matrix when dropped from the bar suddenly is enough to carry one or both ends of said matrix beyond the vertical line 125 of the cell which is to receive it. In all cases and at any speed of movement, it would be a matter of great difficulty, if not wholly impossible, to cause the matrices to drop by gravity in such accurate, vertical relation to its cell as to enter the same without binding or other hinderance due to the displacement of the side-lugs of the matrices.

In order to secure entire accuracy of dis-

tribution it has been thought necessary, heretofore, to drive the matrices upon the distribution bar at a speed so low as to require a considerable increase in the number of matrices, in order that a reserve may always be maintained in the magazine sufficient for the maximum demands under all possible contingencies. This necessity involves a material increase in the capacity of the magazine, and also entails the enhanced cost of the extra number of matrices. By the construction and arrangement last described I am able to effect the distribution at a considerable speed and with perfect accuracy and the magazine may therefore be reduced in dimensions and the number of matrices diminished in an important degree.

I will now point out briefly the system of gearing from which the mechanism derives its movement. Revolution is given by any suitable form of motor to a power-shaft, or main-shaft (Figs. 1 and 2) journaled in the lower part of the frame A of the machine. This shaft is belted to a shaft 72 within the hollow frame A, Fig. 18, upon which is a bevel gear 259, meshing with a similar gear 260, the latter being also within the hollow frame and mounted upon the end of a shaft 261 which is laid in a sleeve-bearing 262 in the wall of the frame A. This shaft inclines from the point where its gear 260 is mounted downward (see Fig. 1) toward the rear side of the table 191, its lower end having support in the extension bracket 243 (Fig. 18) which forms part of the bracket 224. On this end is a bevel-gear 263, meshing with the bevel-gear 244 Fig. 4 which is mounted on the shaft 242 of the lift-cylinder. The shaft 261 is extended through the bracket 243 Fig. 18, and has its end supported in a bearing 264 on the left-hand, rearward angle of the table 191. Close to said bearing 264 it takes a bevel gear 265 which meshes with a similar bevel-gear 266 upon the end of a horizontal shaft 267 supported in bearings 268 rising from the table 191 (Figs. 4 and 18) the end of said shaft nearest the front of the table being provided with a bevel-gear 269, meshing with the bevel-gear 192 on the shaft 190, which gives revolution to the milling-rolls 186. Within the rearward of the two bearings 268, Fig. 4, is arranged an extended hub 270 (Fig. 20) having upon its rearward end, just behind the said bearing, a bevel-gear 271, and upon its other end, just in front of said bearing a heavy flange, or collar 272. The shaft 267 passes loosely through the hub 270, with as little contact as possible. This arrangement is rendered possible by the fact that the extreme rearward end of the said shaft 267 has support in a collar-bracket 273, Fig. 4, projecting from the extension-bracket 243, and therefore requires no support within the hub 270. The bevel-gear 271 carried by said hub meshes with and drives the bevel-gear 229, Figs. 18, 19, which gives revolution to the eccentric 222 by which the ejector-bar 217 is reciprocated. Upon the shaft 267 next

to the front face of the collar 272 is a clutch-disk 274, Fig. 4, splined to the shaft and held normally, against the face of the collar 272 by the pressure of a spring 275, coiled upon the shaft and confined by a rigid collar 276. When controlled by this spring a clutch-connection will be made and maintained between the disk 274 and the collar 272, by means of a locking-pin 277, Figs. 21 and 22, which falls when the disk revolves to the proper point, into an opening 278 in the end face of the collar 272. The clutch-disk 274 is provided with a peripheral channel 279, Fig. 4, for a fork 280 which overhangs the disk and is carried by a guide-bar 281, sliding in bracket-bearings 282, upon the face of the rectangular frame 225. From the collar which unites the fork with said guide-bar projects a finger 283, the end of which enters a slot 284 in a bar 285, arranged at the left-hand and in substantial parallelism with the guide-bar 281. Said bar is extended to the front and connected to the compressor-arm 125, the connection being made for convenience, by means of a slip-joint 286 and set screw 287. When the compressor is drawn back just previous to the quarter-turn of the square, the bar 285 moves with it and as the end of the slot 284 reaches the finger 283, the fork 280 is drawn toward the front of the machine, the clutch-disk 274 is removed from the collar 272 and the ejector-bar 217 ceases to operate. As the square is brought to place and arrested after its quarter-turn, the compressor-arm is moved up to engage the end of the line of matrices upon the side where the cast is made and as the bar 285 moves toward the rear it releases the finger 283 and allows the spring 275 to push the clutch-disk up to the collar 272, thereby establishing the clutch-connection and setting the ejector-bar 217 at work. By this arrangement the ejecting mechanism is in operation only during the time the square is entirely at rest. The pusher-bar 68 Fig. 1, is reciprocated by the shaft 72, as already set forth, which is driven by a pulley 288 Fig. 2, on the power-shaft S, belted to a pulley 289 on the shaft 72. From a pulley on the power-shaft, also, a belt 290 Fig. 2, is led at the rear of the machine up to the two guide-pulleys 291 and after passing over the latter the belt 290 is carried horizontally over the pulley 43 Fig. 1, on the sleeve-bearing 37 Fig. 3, of the sequence-disk 39. Upon the power-shaft S is a worm 293 Fig. 1, meshing with a worm-gear 294 on the vertical shaft 60 which rises in the rectangular frame 225 and at its top receives the sleeve-bearing 59 of the square 50. This vertical shaft has a step-bearing 295 (Fig. 1) and nearly in front thereof rises the upright 128. Upon the shaft 60, above the worm-gear 294 are arranged four separate cams 296, 297, 298 and 299. The lower cam 296 is termed the "lock-up" cam and is the one operating the line-compressor 125 Fig. 4. The next cam 297, is termed the "stop-cam." The third cam 298 counting from the bottom of the series is

known as the "latch-cam" and the fourth and last, indicated, by the numeral 299 is called the "index-cam." The action of the machine is initiated by a pedal 300, Fig. 1, fulcrumed upon a stud 301 on the upright 128. It is unnecessary that these parts be described in this specification as they are fully shown and described in the Letters-Patent dated August 30, 1892, No. 481,920, to which reference has heretofore been made. The cam-series, the mechanism for revolving the square and automatically locking the same after each quarter-turn, and the means for actuating the line-compressor, do not materially differ, in the present instance, from the mechanism shown for the like purposes in said Letters-Patent. Upon the upper end of the vertical shaft 60 is a bevel-gear 302 Fig. 1, meshing with the like gear 105, Fig. 25, on the shaft 95 which revolves the mold-carrier 96. The cam-shaft 158 Fig. 2, which actuates the melting-pot in making connection with the mold and closing the same upon the line of matrices, is driven by a bevel-gear 303 upon the extreme left hand end of the shaft 95, meshing with a similar gear 304 on the cam-shaft. This concludes the series of essential gear-connections of which no description, or a partial description only, has been given in the body of the specification.

What I claim is—

1. In a machine for producing type bars, the combination with a matrix magazine, of a spiral lift to carry the matrices to the magazine, and mechanism for removing the matrices from the spiral lift for distribution, substantially as described.

2. The combination with matrix-assembling mechanism, and matrix-distribution mechanism, of a spiral lift for conveying the matrices from the assembling to the distribution mechanism, and suitable means for moving the matrices from the assembling space or chamber of the assembling mechanism into operative connection with the spiral lift, substantially as described.

3. In a machine for producing type-bars, the combination with a matrix-magazine, of a spiral lift a lift-guide, a distribution bar at the top of the magazine, and mechanism for driving the matrices from the upper end of the lift upon said distribution-bar, substantially as described.

4. In a machine for producing type-bars, the combination with a matrix magazine, having a circular series of cells, of a spiral lift to carry the matrices to the top of the magazine, a circular distribution-bar having one end lying adjacent to the top of the lift, and a wheel-carrier acting on the matrices as they arrive successively at the top of the lift, substantially as described.

5. In a machine for producing type-bars, the combination with a square having a plurality of line-chambers, of means for turning said square intermittently to bring one of said chambers to successive points for assem-

bling the matrices, making the cast, and distributing the matrices; a spiral lift arranged to overhang one end of the line-chamber 70 when in position for distribution, ejecting apparatus to push the matrices from the line-chamber within reach of the lift, and a line-driver for advancing the line to the ejector, said line-driver being engaged and brought 75 into action by the movement of the square which brings the line-chamber under the lift, substantially as described.

6. In a machine for producing type-bars, the combination with a square having a plurality of line-chambers, of a matrix magazine having its cells arranged in circular series, a spiral lift and lift-guide overhanging one side of the square, an ejecting mechanism mounted upon the square, means for actuating said 85 mechanism, a line-compressor and a connection between the ejector gearing and the actuating shaft operated by the movement of the line-compressor, substantially as described.

7. In a machine for producing type-bars, 90 the combination with a magazine having a series of cells for the matrices, of an escapement-mechanism duplicated for each cell and consisting of a spring-impelled latch-bolt having its point normally lying in the path of the 95 lugs of the matrices lying in said magazine, a pivoted lever connected with the latch-bolt and having a rigid lower end or terminal which projects into the path of the matrices when a key is depressed, and is automatically 100 swung outward by the weight of the matrices when the key is released, substantially as described.

8. In a machine for producing type-bars, 105 the combination with a magazine containing a series of cells for the matrices, of separate escapement-mechanism for each cell, a keyboard having keys to operate said escapements, a square having a line-chamber, a line-chute at the end of said chamber, a line-escapement-mechanism mounted upon said 110 chute, and a device carried by a pusher-bar to operate said escapement, substantially as described.

9. In a machine for producing type-bars, 115 the combination with a magazine containing a series of cells for the matrices, of a line-chute stationary at a point beneath the magazine, a series of keys to release the matrices singly from their cells, a square having a line-chamber one end of which lies beneath the 120 line-chute, and a sequence-disk arranged to have continuous movement between the exit ends of the cells and the entrance to the line-chute, substantially as described.

10. In a machine for producing type-bars, 125 the combination with a magazine having a series of cells for the matrices arranged in or upon a circular line, of means for releasing the matrices in orthographical succession 130 from said cells, a square having a line-chamber arranged to receive said matrices, and a continuously moving sequence-disk arranged between the square and the exit-end of the

magazine, to carry the matrices in proper succession to the point where they enter the line-chamber, substantially as described.

11. In a machine for producing type-bars, the combination with a fixed circular matrix-magazine, of a series of keys to release the matrices from their cells, a sequence-disk having continuous revolution upon the fixed axis of said magazine, a series of cell-chutes, between the exit-end of the magazine and the sequence-disk, a square having a line chamber, and a line-chute between the latter and the sequence disk, provided with a clearing-arm, substantially as described.

12. In a machine for making type-bars, the combination with a magazine, having a series of cells arranged upon a circular line, of a series of escapements connected with the cells, a line-chamber having an entrance opening at one end, a reciprocating pusher to drive the matrices out of said opening and into the line-chamber, and an independent escapement arranged in the path of the matrices as they pass to the entrance-opening, substantially as described.

13. In a machine for making type-bars, the combination with a magazine, and with a circular series of cells therein of a series of escapements for said cells, a line-chamber having an entrance-opening, pushing devices to drive the matrices out of said opening and into the line-chamber, an independent escapement interposed in the path of the matrices as they pass to the entrance-opening, and means for operating said escapement and holding the same during a part of each stroke of the pushing-devices, substantially as described.

14. In a machine for making type-bars, the combination with a magazine, and with means for releasing the matrices therefrom, of a line-chamber having an entrance-opening at one end, pushing-devices to advance the matrices from said opening into the line-chamber, and an escapement arranged in the path of the matrices as they pass to the entrance-opening, one of the pushing-devices being provided with a flat, elastic strip arranged to engage its upper surface with a flat lug on the escapement-lever and operate the latter, thereby bringing the lug flat upon the elastic strip and holding the escapement until the pushing-devices complete their forward stroke and part of the return-stroke, substantially as described.

15. In a machine for making type bars, the combination with a main power shaft, a rotating casting mold, mechanism for transmitting motion from the power shaft to the mold, and a tool for dressing the base of the type bar as it lies in the mold, of a countershaft geared with the main power shaft, rotary milling rollers geared together to rotate in unison, one of said milling rollers having its shaft extended to and geared with said countershaft, and mechanism for forcing the type

bar out of the mold and between the rotating milling rollers, substantially as described.

16. In a machine for making type-bars, the combination with a square supported upon a central axis and having a plurality of line-chambers, of a mold-carrier mounted upon an axis lying at a right angle to the axis of the square and means for imparting to both a synchronous movement upon said axis, to bring the several molds upon the mold-carrier successively into position to co-operate with the several line-chambers in the square, substantially as described.

17. In a machine for making type-bars, the combination with a square supported upon a central axis and having a plurality of line-chambers each adapted to receive a line of matrices, of a mold-carrier mounted on an axis arranged at an angle to the axis of the square and having a plurality of mold-casings projecting beyond its margin and means for imparting to said square and mold-carrier a synchronous movement upon their respective axes at suitable intervals, to bring the molds and line-chambers into successive co-action, the angles of the square turning in the open spaces between the adjacent ends of the projecting mold-casings, substantially as described.

18. In a machine for making type-bars, the combination with a square supported upon a central axis and having a plurality of line-chambers, of a mold-carrier mounted loosely upon an axis arranged at an angle to the axis of the square, and having a plurality of mold-casings projecting at intervals beyond its margin, means for imparting to said square an intermittent, fractional revolution, cam-devices for pushing the mold-carrier away from the square prior to said movement, and a clutch-connection to engage the mold-carrier as said separation is effected and cause it to make a fractional revolution upon its axis, substantially as described.

19. In a machine for making type-bars, the combination with a square having a plurality of line-chambers each provided with an entrance-opening at or near one end, of a spring-retracted pusher-block lying in said square adjacent to each of the several entrance-openings, a pusher-bar mounted on an elastic plate having constant reciprocation on the machine-frame and arranged to act upon each pusher-block in succession, and means for giving a fractional revolution to the square at suitable intervals, the angles of the latter being truncated and having openings exposing the outer vertical faces of the pusher-blocks to enable the constantly reciprocating pusher-bar to avoid collision with the square as the latter turns, substantially as described.

20. In a machine for making type-bars, the combination with a matrix-magazine consisting of two concentric shells diminishing in diameter from the top downward and having a series of cells in the intermediate annular

- space, of a lift consisting of a cylinder having a spiral upon its face closely incased by a drum provided with a slot for the outer lugs of the matrices and a lift-guide opposite said slot for the inner lugs, means for driving the matrices out of the line in which they stand far enough to enter said slot and lift-guide and mechanism for revolving the lift-cylinder, substantially as described.
21. In a machine for making type-bars, the combination with a square having a plurality of line-chambers each provided with an entrance-opening, of means for turning said square at intervals upon a central axis, an ejector mounted on the square beneath each entrance opening, a reciprocating bolt to operate the ejector located on the machine-frame beneath the point where the ejector stands when the square is at rest, a lift-guide overhanging one side of the entrance opening of the line-chamber, a vertical lift-cylinder arranged on the other side and having a spiral inclosed by a drum having a slot the open end of which overhangs the side of the entrance-opening opposite the lift-guide, means for continuously revolving the lift-cylinder and a distribution-mechanism at the top of the magazine to which the matrices are delivered by the lift, substantially as described.
22. In a machine for making type-bars, the combination with a square having line-chambers each provided with an entrance-opening for the matrices at one end, of a lift-guide and lift-cylinder arranged upon opposite sides or the entrance-end of one of the line-chambers when the square is arrested, a drum inclosing a spiral on the lift-cylinder and having a slot opening through the lower end of the drum directly over one side of said entrance-opening, ejecting mechanism to drive the matrices successively out of the line chamber and into said slot and lift-guide, means for giving revolution to the lift-cylinder, a magazine having a series of cells into line with which the upper ends of the said lift-guide and slot are brought, a distribution-bar overhanging said cells and having one end in proximity to the top of the matrix when at its upward limit of movement, and a series of finger-carriers moving beneath the said bar and timed to engage the matrices as they reach the top and carry them upon the distribution-bar, substantially as described.
23. In a machine for making type-bars, the combination with a series of cells arranged in a circular line in a matrix-magazine, of a lift-guide arranged to support the matrices upon one side, a lift-cylinder having a drum provided with a slot which receives the lugs on the other side of said matrices, a spiral upon the face of the lift-cylinder closely incased by said drum, said spiral having an upper terminal provided with a horizontal supporting face, a wheel having a fringe of finger-carriers overhanging the cells, and means for giving revolution to said wheel and lift-cylinder, substantially as described.
24. In a machine for making type-bars, the combination with a square having a series of line-chambers of a mold-carrier provided with a series of molds, means for giving partial revolution to both square and mold-carrier at suitable intervals, a movable melting-pot having a spout adapted to engage said molds successively and press the same against the matrices, means for moving said pot and injecting metal into the molds, a planing-tool acting upon the base of the cast type-bar during the movement of the mold-carrier succeeding the casting, milling-rolls operating upon the flat faces of said type-bar as it emerges from the mold, an ejecting device to drive said type-bars out of the molds successively, and a stacker acting thereon after removal, substantially as described.
25. In a machine for making type-bars, the combination with a series of cells for the matrices, each cell consisting of two opposite, parallel slots, or channels, adapted to receive and guide the lugs of the matrices, of a distribution bar overhanging said cells and means for advancing the matrices thereon, the upper terminals between the cells being oppositely beveled to form downwardly converging guides for the lower lugs of the matrices, a separate series of similarly beveled projections being arranged above said terminals to guide the lugs on the upper ends of said matrices, substantially as described.
- In testimony whereof I have hereunto set my hand in presence of two subscribing witnesses.
